UNITED STATES PATENT OFFICE.

CHARLES FESSLER, OF DETROIT, MICHIGAN, ASSIGNOR TO KNOCK DOWN CASE COMPANY, OF DETROIT, MICHIGAN, A CORPORATION OF MICHIGAN.

SHIPPING BOX OR CRATE.

No. 916,852.

Specification of Letters Patent. Patented March 30, 1909.

Application filed December 23, 1907. Serial No. 407,741.

To all whom it may concern:

Be it known that I, CHARLES FESSLER, a citizen of the United States of America, residing at Detroit, in the county of Wayne 5 and State of Michigan, have invented certain new and useful Improvements in Shipping Boxes or Crates, of which the following is a specification, reference being had therein to the accompanying drawings.

10 The invention relates particularly to a fabric especially designed for use in forming the sections or sides of a shipping box or crate, consisting primarily of a series of slats and tie members therefor, and the invention 15 consists primarily in the novel construction of the fabric, in the peculiar means employed for uniting the tie members to the slats to prevent relative creeping movement of the ties, and further to prevent racking 20 of the finished box, and the invention still further consists in certain details of construction as will be more fully hereinafter set forth.

In the drawings illustrating the invention,—Figure 1 is a sectional perspective view of a crate or box section formed from my improved fabric; Fig. 2 is a cross section therethrough taken on lines $x-x$ of Fig. 1; Figs. 3 and 4 are sectional perspective views of modified forms of the fabric; and Fig. 5 is a sectional perspective view showing the preferred arrangement of the slat sections.

In the drawings thus briefly described,—reference being had particularly to Fig. 1,—A represents a section of a shipping box or crate composed of an open-centered frame formed of side members a and ends b , with my improved fabric arranged over the 40 framework intermediate the sides, as shown. The fabric consists primarily of a series of slats, as B, arranged in parallel alinement and extending in this instance longitudinally of the framework, and a series of tie members C uniting the slat series and secured at their respective ends to the frame sides in any suitable manner.

In forming the fabric, the slats are arranged side by side in transverse alinement, 50 with the tie members extending crosswise thereof, the ties being preferably flat metallic bands.

To prevent creeping movement of the ties in relation to the slats, I have shown (reference being had to Fig. 4) means for uniting

the tie members to the slats extending through the ties, the means being preferably,—though not necessarily,—a rivet c which pierces the band or tie and has a 60 clenching engagement with the slat.

For the purpose of preventing racking of the section and the consequent distortion of the form of the finished crate, I employ in the construction of the fabric two securing devices d e in connection with each slat, 65 these devices being spaced apart and extending through the tie as previously set forth. This produces a structure that will withstand all strains that may be imposed upon the crate at any angle or corner with- 70 out permitting distortion.

In Fig. 1 I have shown the preferred form of fabric consisting of a series of slats and the tie members as previously set forth, but the slats in this instance are cut or sawed 75 longitudinally, forming complementary sections f g adapted to be superimposed as shown, while the tie member or band extends across the slat series intermediate the sections. The slat members may be united 80 in any suitable manner, but I have preferably connected them by two spaced fasteners c' d' ,—preferably rivets,—which extend through the tie member for the purpose previously set forth. Also to further 85 strengthen the fabric I superimpose slat sections in which the grain runs in different directions in the manner indicated in Fig. 5. The fabric thus formed is light and durable, the tie members and slats are held against 90 relative movement, the slats are incapable of any turning movement in relation to one another that will permit a distortion of the box or crate, and the structure as an 95 entirety is capable of being manufactured at small cost.

What I claim as my invention is,—

1. A fabric for the manufacture of shipping crates or boxes consisting of a series of slats formed each of complementary 100 superimposed sections, and a series of metallic tie members extending crosswise of and continuously over the slats intermediate of the sections, the ties being respectively riveted to each slat.

2. A fabric for the manufacture of shipping crates or boxes, comprising a series of longitudinally sawed slats, the sections of each being superimposed, a series of flat metallic bands extending transversely of the 110

slats intermediate the sections and continuously across the series, and securing devices extending through the respective bands and the sections of each slat in proximity to the side edges uniting the parts.

3. A fabric for shipping crates or baskets, comprising a series of slats formed each of longitudinal sections, a series of tie members crosswise of the slats intermediate the

sections, and uniting means for the sections extending through the tie members.

In testimony whereof I affix my signature in presence of two witnesses.

CHARLES FESSLER.
